UNITED STATES PATENT OFFICE.

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS.

STALL-FRAME CONSTRUCTION.

1,256,457.

Specification of Letters Patent. Patented Feb. 12, 1918.

Application filed July 19, 1915. Serial No. 40,620.

To all whom it may concern:

Be it known that I, HOWARD J. FERRIS, a citizen of the United States, residing at Harvard, in the county of McHenry and State of Illinois, have invented a new and useful Improvement in Stall-Frame Construction, of which the following is a specification.

My invention relates to improvements in stall-frame construction, and, more particularly, to a manner of constructing the arms by which the stall fronts are secured. More immediately, it is the object of the invention to provide a construction of arm adapted for attaching the front frame member of the stall to the stall partitions and to pillars and other supports.

In the construction of modern dairy barns, it is customary to make use of cattle stalls and stanchions constructed almost entirely of steel framing and usually arranged in groups or rows of stalls placed side by side and tied together by suitable securing and supporting means. Where stalls are stalled in this manner, it becomes desirable to provide means by which the spacing of the stalls, *i. e.*, the width from one stall partition to the adjacent stall partition may be varied in order to utilize to the best advantage the space available for the row of stalls in the barn. Thus, the width between adjacent supporting pillars of a barn structure might be either slightly less or slightly greater than a multiple of the normal width of a stall, and it will therefore be desirable to alter the normal or stock width of a stall in order to evenly divide the space between the pillars. It is the specific object of my invention to provide a stall-frame construction, and more particularly a construction of supporting arm for the stall fronts by which this alteration in the width or spacing of the stalls may be effected with the greatest facility.

My invention will be more readily understood from the following detailed description of one specific embodiment of the same, in connection with the accompanying drawings, in which—

Figure 1 is a front elevation of a pair of adjacent stalls connected in the manner contemplated by my invention. Fig. 2 is an enlarged plan view of the form of stall supporting arm shown in Fig. 1. Fig. 3 is an

enlarged elevation of the pair of supporting arms which connect the two stalls shown in Fig. 1. Fig. 4 is a section on the line 4 of Fig. 3. Fig. 5 is a longitudinal section on the line 5 of Fig. 2. Fig. 6 is an enlarged perspective view of the four elements which make up the supporting arm shown in the preceding figure; and Fig. 7 is an enlarged perspective view of a form of securing means adapted to replace the pipe clamp of the preceding figures, and to adapt the supporting arm for attachment to a pillar when used on an end stall.

Referring more particularly to the drawings, the numeral 10 designates an arched stall front which will commonly have its legs secured to the curb 11 of the barn and will carry a stanchion 12 swung from its top member. The stall front 10 will commonly be constructed of tubular steel. In the drawings, I have shown two adjacent stalls 10 and 10¹ which are separated by a partition member consisting of a tubular bar 13 mounted between the stall fronts and extending backwardly the length of the stall and secured to the floor at its rear end in any suitable manner. The manner of securing the rear end of the partition bar 13 is well understood in the art and forms no part of my invention, and I have therefore omitted the illustration of the rear end of the bar in the drawings. The stall fronts 10, 10¹ are secured to one another and supported in a vertical position by horizontal arms 14, 14¹, which are connected in alignment with one another to the front end of the partition bar 13.

It will be understood that the stall fronts 10 and 10¹ are commonly manufactured as a stock commodity in certain predetermined sizes, and as pointed out, it becomes advantageous under certain conditions of installation to alter the distance between or the width of the stalls. This may be effected by varying the lengths of the horizontal arms 14, 14¹, and it is with the construction of these arms that my invention is particularly concerned.

Referring to Figs. 2 to 7 of the drawings, in which I have shown in detail the construction of my supporting arms, it will be seen that each arm consists of a stall-engaging end designated generally by 15, a partition-engaging end designated by 16 and an inter-

mediate portion or spacer 18 lying between the ends. The stall-engaging end 15 is made up of conjugate pipe clamps 19, 20, each provided with ears through which securing bolts 21 may pass to clamp the parts about the tubular frame-member 10 of the stall. The clamp section 20 is provided with a cylindrical boss 22 which is reduced on its outer end to form a shoulder 23. The end 16 of the arm is formed as a single semi-cylindrical pipe clamp (see Fig. 6) and carries also a boss designated 24 on the outer face of which is formed a spider 25. The spacer member 18 of the arm 14 telescopes over the reduced ends of the boss 22 and over the peripheral surfaces of the spider arms 25 and seats against the shoulder 23 and the outer face of the boss 24. The parts are locked in the assembled position described by a tie-rod 26 headed as at 27 and threaded as at 28 on the other end. The headed end of the tie-rod is preferably squared or otherwise formed to engage a suitable aperture in the boss 22 to prevent rotation of the tie-rod relative to the boss, while the threaded end 28 of the rod is screwed into a tapped-bore 30 in the boss 24.

The arm 14¹ will be a duplicate of the arm 14, but in mounting the parts on the stall frames the partition-engaging ends 16 and of the arms 14, 14¹ will be reversed, as shown in Fig. 3 of the drawings, so that the two semi-circular ends 16 will completely embrace the tubular partition member 13. The two stall arms are secured to one another and to the partition by a through-bolt 31 for which apertures 32 are provided in the clamping ends 16 and in the partition member.

40 In place of the semi-circular pipe clamp member 16 which is used on the arms 14, 14¹ when they form a connection between two adjacent stalls and the partition bar, I may form the outer end member of the arms as a flattened head, as shown in Fig. 7 and designated by 32. This head may be provided with bolt-holes 33 by which it may be secured to a supporting pillar of the barn structure by means of an angle-plate 34 as shown in Fig. 1. In order to provide a space for the end of the tie-rod 26 in case the latter should project beyond the boss 24 in the form of the arm-end shown in Fig. 7, I provide the plate 32 with a central recessed portion 35.

From the foregoing description it will be understood that the arms which support and space the stall fronts each consist essentially of four members, *i. e.*, a stall-engaging end, 60 a support-engaging end, a spacer for separating the ends, and a tie-member for securing the ends against the spacer. By my construction of these parts, the length of the supporting arm may be readily altered 65 by merely altering the lengths of the spacer

and tie-rod. The former element may be made of standard tubing which is readily procurable and is manufactured and sold as a stock commodity. The tie-rod or tension member which holds the ends of the 70 arm against the spacer is likewise a standard or stock article of commerce, being nothing more or less than a common carriage bolt. In order to vary the lengths of the supporting arms of the stall construction, it is therefore necessary only to make use of spacing tubes 18 and tie-rods or bolts 26 of the desired length. These parts are both readily procurable and may be cut to the exact length desired by any person 75 of ordinary skill at the time the stalls are put in place in the barn structure. In manufacturing the parts of stall construction for sale, the spacers 18 and tie-rods or bolts 26 may be made of the maximum length 80 which will be required, and these parts may then be cut down to the exact length desired in any particular installation at the time they are to be put in use, with the 85 minimum amount of trouble.

90 While I have shown and described in considerable detail one specific embodiment of my invention, it is to be understood that this is illustrative only and that I do not regard my invention as limited to the details of construction as shown and described, except in so far as I have included such limitations in the terms of the following claims, in which it is my intention to claim all 95 novelty inherent in my invention as broadly 100 as is permissible in view of the prior art.

What I claim as new and desire to secure by Letters Patent is—

1. In combination with a stall front and a support therefor, a supporting arm between said front and support comprising a stall engaging end, a support engaging end, and an intervening spacing member securing means for said ends, and a single means carried by said ends for detachably engaging and holding said intervening spacing member in place whereby the position of the stall front with reference to its support may be adjusted by varying the length of 105 said spacer member.

110 2. In combination with a stall front and a support therefor, a supporting arm between said front and support comprising a stall engaging end, a support engaging end, means for securing said ends in place, said ends having opposed cylindrical bosses, a tubular spacer member interposed between 115 said ends and telescoping over said opposed bosses and a single tie rod extending from one end to the other through the bore of said tubular spacer member.

120 3. In combination with a pair of adjacent stall fronts and a partition bar lying between and spaced from said stall fronts, a pair of alining arms extending between the 125 130

stall fronts and secured to said partition bar, each arm comprising a stall engaging end, a bar engaging end, means for securing said ends, an intervening spacer member extending between the ends whereby the distance between said stall fronts may be adjusted by varying the length of said spacer member and a single means for securing the two ends and spacer member in place.

HOWARD J. FERRIS.
